UNITED STATES PATENT OFFICE.

PERCY RUSSELL, OF BROOKLYN, NEW YORK, ASSIGNOR TO ELECTRO DENTAL MANUFACTURING COMPANY, OF PHILADELPHIA, PENNSYLVANIA, A CORPORATION OF PENNSYLVANIA.

SWITCH FOR DENTAL INSTRUMENTS

1,242,115.

Specification of Letters Patent.

Patented Oct. 2, 1917.

Application filed August 15, 1914. Serial No. 856,940.

To all whom it may concern:

Be it known that I, PERCY RUSSELL, a citizen of the United States, residing in Brooklyn, Kings county, New York, have 5 invented certain Improvements in Switches for Dental Instruments, of which the following is a specification.

One object of my invention is to provide a relatively simple and substantial electric switch, particularly designed for use in connection with dental and medical instruments employing an electric current and having its parts so designed and constructed as to prevent injurious arcing at its contacts, 10 even when comparatively heavy currents are broken.

Another object of the invention is to provide a hand switch with a novel form of sleeve-operated movable contact, together 20 with a novel form of inclosing casing consisting, in this case, of an operating sleeve provided with a recess for the reception of the projecting part of one of the contacts, whereby a relatively wide separation of the 25 switch members is possible.

These objects and other advantageous ends I secure as hereinafter set forth, reference being had to the accompanying drawings in which;

30 Figure 1 is a side elevation of the instrument constituting my invention;

Fig. 2 is a longitudinal vertical section, further illustrating the detail construction of the device shown in Fig. 1, and showing 35 the operating sleeve in such a position as to close the switch;

Fig. 3 is a vertical section, similar to that of Fig. 2, but showing the switch open;

Fig. 4 is a perspective view of the insulating member supporting the contacts, and

Fig. 5 is a detached perspective view of the contacts and an associated part.

In the above drawings 1 represents a tubular casing, threaded at one end for the reception of the correspondingly threaded part 2 of any instrument to be supplied with current, such for example, as the cauterizing device 3, and also threaded at its rear end for the reception of an insulating bushing 21. At the inner end of said device 3, are a pair of concentric terminals 4 and 5, insulated from each other and from the body, and so arranged that the terminal 5, which is of smaller diameter than the terminal 4, projects beyond the same so as to extend

into the forward end of the tubular casing 1. This latter has a side opening 6, immediately adjacent its forward end and is also provided with a slot 9 to the rear of said opening.

Both the slot and opening are covered by an operating sleeve 7, which adjacent its forward end is formed of insulating material with a side swelling or hollow lateral enlargement 8. The elongated slot 9, which is in line with the opening 6, is designed for the reception of the inwardly projecting end of a screw 10 carried by the sleeve 7 in such manner as to definitely limit the possible amount of sliding movement thereof as well as to prevent its rotation on the tubular casing 1. In addition this screw is employed to directly activate the switch hereafter described.

Mounted within the casing is a substantially cylindrical elongated body of insulating material 11 (Fig. 4) held in place by a set screw 12, projecting inwardly through the wall of the casing, as shown in Fig. 1, and having two longitudinally extending recesses 13 and 14 formed in its opposite sides.

The first of these has mounted in it one end of a spring bridge or contact piece 15, constituting the movable member of the switch and this is of such length that its free end is capable of being moved into engagement with the terminal 5 of the electro-receptive device 3. From Fig. 5, it will be noted that this free end of the strip is offset to form a number of steps or shoulders and with the insulating piece 11 is so mounted in the casing 1 that when the sleeve 7 is in its rear position, its extremity 15^a extends through the opening 6 into the hollow of the swelling or projection 8. One of the shoulders 15^b of the strip 15 is so placed as to be engaged by the inwardly projecting end of the screw 10 when the sleeve 7 is so moved as to bring said screw into the forward end of the slot 9, and as a consequence 100 the strip 15 is so formed that under these conditions its extremity 15^a will contact with the terminal 5.

The recess 14 of the insulating piece 11 contains three substantially parallel strips 105 16, 17 and 18, of which the second is of insulating material and effectually separates the other strips which are respectively connected to conductors 23 and 24, in turn connected to a source of current supply. These 110

strips are held in their recesses by windings of thread or cord, extending around the piece 11 in recesses 19. The strip 18 extends along that side of the casing 1 opposite the opening 6 and it is formed with a projecting contact shoulder 18^a at its extremity, so placed as to be engaged by the cylindrical terminal 4 of the instrument 3 which is screwed or otherwise inserted within the open end of the casing 1.

This extremity of the strip 18, as well as the end 16^a of the strip 16, is free to yield to a slight extent and is slightly curved in order that the terminal 4 may slide under it while being maintained in electrical contact therewith, it being noted that said strip is insulated from the wall of the casing 1 by a suitable body 20 of insulating material. An insulating bushing 21 is mounted in the rear end of the casing 1, and has an opening for the passage of a cable 22 containing the conductors 23 and 24, of which one is electrically connected to the strip 16, while the second is connected to the strip 18.

Assuming that an electro-receptive device such as the cautery 3 is mounted in the forward end of the casing 1, its terminal 4 will be in electrical engagement with the end of the strip 18, although the circuit will be open, since as shown in Fig. 3, the strip 15 normally lies with its extremity 15^a in the outwardly swelled portion of the sleeve 7, so that the terminals 15^a and 5 are disconnected. When, however, said sleeve is moved forwardly in casing 1, the end of the screw 10 strikes the inclined shoulder 15^b of the strip 15, moving its free end laterally until its extremity 15^a engages the terminal 5 of the instrument 3. At the same time that this occurs, the offset portion 15^c of said strip likewise electrically contacts with the extremity 16^a of the strip 16, thus closing the circuit at two points. The sleeve 7 is held in its forward position by reason of the fact that the end of the screw 10 rides over the more or less blunt angular surface between the offset portion 15^c and shoulder 15^b and rests on the forwardly inclined part of said offset portion.

When the sleeve 7 is moved rearwardly to cut the instrument 3 out of circuit, the end of the screw 10 is moved back from the angular surface or shoulder between the parts 15^c and 15^b of the strip 15, whereupon it slides down the relatively steep inclined shoulder 15^b and because of the springy nature of said strip, is caused to complete its rearward movement at a relatively high speed. As a consequence, the strip 15 simultaneously breaks the circuit at a plurality of points, for at the same time its extremity 15^a disengages the terminal 5, its offset portion 15^c breaks contact with the extremity 16^a of the strip 16. Owing, therefore, to the quick breakage of the current at

the two points, there is relatively little arcing, even though the current be relatively heavy and the voltage high. By permitting the end 15^a of the strip 15 to enter the recess 8 in the sleeve 7, I am enabled to secure a wide separation between said strip and the two members which it electrically connects, thus still further diminishing the possibility of injury from arcing.

I claim:

1. The combination in an electric switch of a supporting structure formed to receive an instrument to be supplied with current; a fixed contact; a laterally flexible bridge piece; with a member slidably mounted on said supporting structure to move longitudinally thereof and operatively connected to the bridge piece for moving the same into direct engagement with a terminal of the instrument and said fixed contact.

2. The combination in an electric switch of a supporting structure formed to receive an instrument to be supplied with current; a fixed contact; a bridge piece of spring material; means for bending said bridge piece into a position to engage said fixed contact and the terminal of said instrument, said means consisting of a sleeve mounted to slide longitudinally of the structure and operatively connected to the bridge piece.

3. The combination in an electric switch of a tubular structure for the reception of an instrument to be supplied with current; a relatively fixed contact mounted in said structure; a movable contact also within the structure; with a sleeve slidably mounted on the tubular structure and having a portion movable longitudinally of said structure and operative on the movable contact to bend it laterally into engagement with the fixed contact and with one terminal of the instrument attached to the structure.

4. The combination in an electric switch of a slotted tubular structure for the reception of a portion of the instrument to be supplied with current; a relatively fixed contact and a bridge piece mounted in the structure and movable laterally thereof, with a sleeve slidably mounted on the tubular structure and having a portion projecting through the slot into engagement with the bridge piece for moving the same into engagement with the fixed contact and with a terminal on the instrument.

5. The combination in an electric switch of a tubular structure having an opening; two relatively fixed contacts in said structure; a sleeve slidably on the structure and having a recess; with a movable contact member mounted within the structure so as to be electrically independent of the contacts when the switch is open and placed to be operated by the sleeve, said member extending through the opening of the tubular

structure into the recess of the sleeve and being movable by the latter from said recess into electrical engagement with the fixed contacts.

5. 6. The combination in an electrical switch of a tubular structure; a conductor mounted therein and having a terminal for engagement with one of the terminals of an electro-receptive device; a relatively fixed contact; a spring strip; and means for deflecting said spring strip transversely of the tubular structure to cause it to simultaneously engage the fixed contact and a second terminal of the electro-receptive device.
10. 7. The combination in an electric switch of a tubular structure; a conductor mounted therein and having a terminal for engagement with one of the terminals of an electro-receptive device; a relatively fixed contact; a spring strip; and means for causing said strip to simultaneously engage the fixed contact and a second terminal of the electro-receptive device, said means consisting of a sleeve slidably mounted to move longitudinally of the tubular structure and operatively connected to said spring strip.
15. 8. The combination in an electric switch of a supporting structure; a slideable sleeve permanently mounted thereon and having a projection; two relatively fixed contacts carried by the supporting structure; with a bridge piece having a shoulder and movable into engagement with said contacts when said shoulder is engaged by said projection.
20. 9. As a new article of manufacture, an electric switch consisting of a tubular structure; two terminal contacts of which one is placed to be engaged by one terminal of an electro-receptive device; a bridge piece consisting of a spring strip rigidly held at one end and extending adjacent the second contact; with a sleeve slidably mounted on the tubular structure and including a portion coacting with said bridge piece for bending the same into simultaneous engagement with the second contact and with the second terminal of the electro-receptive device.
25. 10. The combination in an electric switch of a metallic tube; two insulated contacts therein; a movable conductor constituting a bridge piece and electrically independent of said contacts when the switch is open; with a sleeve of insulating material slideable on the tube and having a portion placed to hold the bridge piece in electrical engagement with said contacts when said sleeve occupies a predetermined position.
30. 11. The combination in an electric switch of a tube having a side opening; a circuit terminal and a spring contact extending into said tube; a spring strip mounted in the
- tube; a sleeve slideable on the tube and having a hollow enlargement immediately adjacent the side opening thereof; with means for moving and holding the spring strip in engagement with the terminal and with the contact when the sleeve is moved into a definite position, said strip being disengaged from said terminal and contact and projecting into the hollow enlargement of the sleeve when the latter occupies a second position.
35. 12. The combination in an electric switch of a tube; a body of insulating material mounted therein; two conductors attached to said body and constituting the terminals of an electric circuit; a movable contact also carried by said insulating body; a sleeve slideable on the tube; and a member on the sleeve operative upon the movable contact for holding the same in electrical engagement with the terminals when the sleeve is in one position, said contact being disengaged from said terminals when the sleeve is in a second position.
40. 13. The combination of a tube for the reception of an electro-receptive device; a contact forming part of an electric switch and mounted in said tube; a conductor electrically independent of said switch and movably mounted in the tube; with means longitudinally movable on the tube for moving said conductor laterally of the tube to electrically connect said contact and a terminal of the electro-receptive device.
45. 14. The combination of a tube; two terminals extending in substantially the same straight line within said tube and forming part of an electric switch; a spring strip mounted in the tube and electrically independent of said terminals; with means for laterally moving said strip to cause it to simultaneously engage said two terminals.
50. 15. The combination of a tube; two terminals extending in substantially the same straight line within said tube and forming part of an electric switch; a shouldered spring strip mounted in said tube and electrically independent of said terminals; with means for laterally moving the strip to cause it to simultaneously engage the two terminals; said means including a sleeve slideable longitudinally of the tube and operative upon the shouldered portions of said spring strip.
55. In testimony whereof, I have signed my name to this specification, in the presence of two subscribing witnesses.

PERCY RUSSELL.
